UNITED STATES PATENT OFFICE.

CLARENCE N. COMATI, PETER E. KEKENES, AND NICHOLAS J. PETERS, OF BIRMINGHAM, ALABAMA.

DESIGN FOR A BOTTLE OR SIMILAR ARTICLE.

Application filed September 27, 1926. Serial No. 19,188. Term of patent 14 years.

To all whom it may concern:

Be it known that we, CLARENCE N. COMATI, PETER E. KEKENES, and NICHOLAS J. PETERS, citizens of the United States, residing at Birmingham, in the county of Jefferson and State of Alabama, have invented a new, original, and ornamental Design for a Bottle or Similar Article, of which the following is a specification, reference being had to the accompanying drawings, which form a part hereof, and in which—

Fig. 1 is a side elevation of a bottle showing our design; and

Fig. 2 is a section on the line II—II of Fig. 1.

We claim as our invention:

The ornamental design for a bottle or similar article, as shown.

In testimony whereof, we affix our respective signatures.

CLARENCE N. COMATI.
PETER E. KEKENES.
NICHOLAS J. PETERS.
